FLATWORK KNITTING MACHINE

Paul G. Stroud, Belmont, N. H., assignor to Belmont Hosiery Company, Belmont, N. H., a corporation of New Hampshire

Application February 21, 1938, Serial No. 191,625

16 Claims. (CL 66—127)

This invention relates to knitting machines of the so-called "flat type" and is more especially concerned with those designed for the knitting of full-fashioned hosiery.

5 It is now a common custom in knitting machines of this type to feed the silk for knitting the main portion of a stocking alternately from three spools, cones, or other sources of supply. This expedient has the result of averaging any 10 unevenness in the silk, and thus reducing to a minimum the tendency to produce horizontal rings.

The present invention aims to simplify the mechanisms provided for the purpose of feeding 15 the thread in this manner and to devise an arrangement which will be more reliable in operation and will require less care, skill and attention on the part of the machine tender or operator.

The nature of the invention will be readily understood from the following description when 20 read in connection with the accompanying drawings, and the novel features will be particularly pointed out in the appended claims.

In the drawings,

25 Figure 1 is a transverse, sectional view through the thread carrier bars and adjacent parts of a full-fashioned knitting machine, and illustrates a construction embodying features of this invention;

30 Fig. 2 is a view approximately on the line 2—2, Fig. 1, with parts broken away in order better to illustrate the details of construction;

Figs. 3 and 4 are plan and front views, respectively, of the thread feeding instrumentalities 35 shown in Figs. 1 and 2 in their operative positions in a knitting machine, these views being somewhat diagrammatic in character; and

Fig. 5 is an angular view of a portion of one of the thread carrier bars and the equipment provided by this invention for operating it.

In the drawings, the numerals 1, 2 and 3 designate certain of the thread carrier bars of a full-fashioned knitting machine mounted in the usual way, the bars carrying thread guiding fingers 4, 45 5 and 6, respectively, Fig. 1. In the operation of the machine these fingers feed thread alternately to the needles 7 of a single section of a knitting machine, while other fingers mounted on the bars perform the corresponding thread

50 feeding functions for other sections. The illustration of all of these parts in the drawings is purely conventional, since they are all well-known elements of any full-fashioned machine and accordingly, no detailed illustration of them is necessary. The machine is also shown convention-

ally as equipped with the usual friction driving head 8 mounted on the customary driving rod 10 and guided on another rod 12.

The customary three-carrier feeding mechanisms are so organized that one thread carrier makes its thread feeding stroke and then remains idle while the second makes its stroke, this, in turn, remaining inactive while the third moves across the section and feeds thread to the needles. These operations are repeated, the fingers feeding their thread to the needles alternately and in a predetermined fixed order. The mechanism provided by this invention produces this same result but with a much simpler construction.

Referring to Figs. 2, 4 and 5, it will be seen that 15 the thread carrier bar 3 is equipped with a supplemental bar or bridge piece 14. Formed integral with the bar 14 are two end plates 15—15 which are welded or riveted securely to the bar 3. The thread guiding fingers 6 and 6' are secured to the 20 lower side of the bar and extend downwardly into their normal relationship to the knitting instrumentalities. Functionally the bar 14 forms a part of the carrier bar 3, and it is made separate from it as a matter of manufacturing convenience and to reduce the expense of making change-overs. At its right-hand end the bar 14 is notched, as best shown in Figs. 2 and 5, to provide two shoulders 16 and 17 for engagement with pawls for driving the bar. Between these 25 shoulders it is equipped with a cam 18 which is secured rigidly to the bar. As best shown in Fig. 2, the thread handled by the thread finger 6 is led from a suitable source of supply through a thread guiding hole 20 extending into the end 30 of the bar 14 or the plate 15 of this bar and emerges at the eye 21 directly over the entrance to another thread passage 22 in the lower part of the plate. This passage guides the thread into the thread guiding portions of the finger 6. It 35 should be understood that this same construction is used at the opposite end of the bar 14. Also, that each of the other thread carrier bars 1 and 2 is equipped with a supplemental bar 14 and parts associated with it exactly like the arrangement just described.

For the purpose of operating these thread carrier bars selectively and in the proper order, the reciprocating head 8 is equipped with three double acting dogs, indicated at 23, 24 and 25, respectively. These dogs are mounted side by side on a bar or rod 26 so that they can rock about the axis of this member, the bar or rod being secured rigidly in the head 8. The dogs are mounted 40 above and in the same plane with the respective 45

50 55

carrier bars and each cooperates with one bar only. Since they are all alike and the cooperative relationship between each and its bar is like that of the others, a description of one only is required.

Referring to Fig. 2 it will be seen that the dog 25 is provided with two integral pawls, indicated at *a* and *b*, respectively, each designed to engage the notches 16 and 17, and when so engaged and moved with the reciprocating head 8, to traverse the carrier bar 3 through its operative path of movement. The dog can rock on the rod 26 into position to bring either pawl into cooperative relationship to its bar, and a spring pressed ball 27 bearing on the rod 28, which is either integral with, or rigidly secured to, the rod 26, cooperates with the inclined and flattened surfaces of the part 28 to hold the pawl yieldingly in contact with the respective shoulders 16 and 17. Also, the range of swinging movement of the pawl is limited by two screws 38 and 39 threaded through the opposite sides of the dog where their inner ends will engage the opposite sides of the bar 28, the screws being adjustable and being provided with check nuts to secure them in their adjusted positions.

Assuming that the dog 25 is in the position shown in Fig. 4, and that the head 8 has just completed its movement toward the right, then it is clear that the thread guiding finger 6 will have just completed a thread feeding stroke. A friction mechanism of any suitable type is provided to hold all of the thread carrier bars in stationary positions except when they are being positively driven by the head 8 and its connections with the bars. Consequently, when the dog 25 arrives in the position shown in Fig. 4 and starts upon its return stroke toward the left, its operative engagement with the bar 3 will be interrupted. In other words, as it moves toward the left, the pawl *b* will be withdrawn from the notch 17 and its lower edge will strike the cam 18. As it continues to move toward the left the engagement of these two parts will rock the dog 25 in a counter-clockwise direction until the pawl *a* is brought down upon the upper surface of the bar 14. The spring pressed ball 27 serves to hold it in this position and, in fact, presses it lightly against said bar. The dog will remain in this position while the head 8 makes one complete reciprocation. That is, it completes its stroke to the left, Fig. 4, and then another stroke to the right. Upon its return it brings the dog back into the position shown in Fig. 2 where the pawl *a* drops into the notch 16. Upon the next stroke of the dog toward the left, it will carry the bar 14 with it, and the finger 6 will again feed thread to the needles. As the head reverses, the pawl *a* will move out of the notch 16, thus interrupting its driving connection with the bar 14, and leaving the bar in an idle position. As it moves toward the right it will be knocked over into approximately its position shown in Fig. 4, and it will remain in this position while the head makes one complete reciprocation but at the completion of that reciprocation the pawl *b* will drop into the notch 17 and, as the head moves toward the right, will carry the bar 14 back into the position shown in Fig. 4 again.

Thus the bar 3 and the thread guiding fingers which it carries will make one thread feeding movement and then rest or remain idle while the head 8 makes a complete reciprocation. In the meantime, however, the other two bars 1 and 2 have been similarly operated. During the first

stroke of the head, immediately after the operation of the bar 3, the bar 2 will be operated by its dog and will feed thread to the needles. It will then remain idle while the head makes two additional strokes, and during the first of these 5 strokes the bar 1 will be operated by its dog to feed thread to the needles. Upon the next succeeding stroke the bar 3 comes into operation again. Thus in this particular arrangement the bars are operated alternately in the order 3, 2, 1, 10 3, 2, 1, etc.

It will be observed that the operation of each dog is independent of that of the others and depends solely upon the reciprocating movement of the head 8 and the engagement of the dog with 15 its respective bar or the cam mounted on that bar. Its shift from one operative position to the other is effected by its movement of translation relatively to its respective bar, and the interruption and re-establishment of its driving connections with its bar in the proper timed relationship to the movement of the head is also controlled by the relationship of the dog and the bar to each other and the relative movement of translation imparted by the head. Consequently, by 20 mounting the three dogs properly with reference to their respective bars, correctly adjusting their range of oscillating movement, setting one bar to the right and the other two to the left, or vice versa, and initially disposing the dogs in their 30 proper angular relationship to their respective bars, the apparatus may be made to operate the three bars in the correct timed relationship to each other. This relationship thereafter will be maintained automatically.

Preferably the rod 26 is made integral with, or is secured rigidly in, a member 32, Figs. 1 and 3, which fits into a socket in the central member of the head and is pivoted there on the pin 33. This member is of rectangular cross-section and fits snugly between the walls of the socket so that it supports the bar 26 rigidly with reference to the head. At the same time this member can be swung upwardly on the pivot 33, carrying the dogs with it, into a position where they will all 45 be clear of the bars so that either the dogs or the bars themselves can be removed, adjusted, or replaced, as may be found necessary. After being returned to its operative position, it is secured there by a wing screw 34, Fig. 3.

Collars 35 and 36 fitting over the rods 26 and 28 are secured to them by set screws and serve to hold the assembly of dogs 23, 24 and 25 against movement axially of the rod 26 out of their operative positions.

Any suitable form of friction mechanism may be utilized to hold the bars 1, 2 and 3 in stationary positions except when they are being driven by their respective dogs. A typical arrangement is illustrated in Figs. 3 and 4 in which leather pieces 60 37-37 secured to the lower edge of a pressure plate 38 are arranged to bear on this entire series of rods, the plate itself being pressed downwardly toward the rods by one or more spiral springs 48 each encircling a screw 41 which is threaded into a portion of one of the bearing brackets 42 in which the thread carrier bars are supported for longitudinal reciprocating movement. Any other convenient way of applying this pressure may, however, be used.

As well known by those skilled in this art, a full-fashioned knitting machine is customarily equipped with several more thread-carrier bars than those shown at 1, 2 and 3. It is unnecessary to illustrate them here, however, since they are 75

not directly concerned with the present invention. It will also be understood that the particular relationship which the bars 1, 2 and 3, Fig. 1, bear to the other bars may be changed as circumstances require. That is, the three bars just mentioned, as shown in Fig. 1, are the three lowest of the entire series of bars but they may equally as well be the three upper bars, or they may be located in any other relationship with reference to the bars not used for this particular purpose.

It will also be understood that each of the bars shown carries additional thread fingers for guiding thread to the respective banks of needles, each of these bars running the entire length of the machine.

From the foregoing it will be appreciated that the invention provides an exceptionally simple mechanism for operating the thread carriers utilized in such systems as that known as the "three-carrier system" for feeding threads alternately to the needles during the knitting of the leg portion of a stocking. Because of its simplicity it can be manufactured and installed economically. In addition, it is of such a nature that it is extremely reliable, is not likely to get out of order, and when once properly adjusted, requires a minimum of attention on the part of the operator.

30 While I have herein shown and described a typical embodiment of my invention, it will be understood that the invention is susceptible of embodiment in other forms without departing from the spirit or scope thereof.

35 Having thus described my invention, what I desire to claim as new is:

1. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, means carried by said head for reciprocating said bars, and parts acting through the movement of said head relatively to the respective bars for causing said means to operate said bars intermittently and in a predetermined order.

2. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, means carried by said head for reciprocating said bars, and parts on said bars cooperating with said means to cause the latter to operate said bars alternately.

3. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, means carried by said head for reciprocating said bars, and parts on said bars cooperating with said means during the reciprocation of said head to establish and interrupt driving connections between said means and said respective bars in such a timed relation as to operate the bars intermittently and in a predetermined order.

4. In a flat knitting machine, the combination with a series of thread carrier bars mounted side

by side for reciprocating movement in parallel paths and thread guides on said bars for feeding threads to the needles of the machine, of a reciprocating head mounted for movement in a path parallel with and closely adjacent to said bars, means carried by said head for reciprocating said bars, and means operated by the reciprocation of said head relatively to said bars to shift its driving connections from one bar to another and thus to operate them intermittently and in a predetermined order and to reverse the direction of movement of each bar for successive operations thereof.

5. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, and means carried by said head for reciprocating said bars comprising driving pawls mounted on said head and operative to engage parts on the respective bars to reciprocate them, said means and said parts cooperating with the travel of said head to interrupt the driving relationship between each bar and its respective pawl for a predetermined number of strokes of the head immediately following the completion of a stroke of the bar.

6. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, means carried by said head for reciprocating said bars comprising a plurality of dogs carried by said head, one for each bar, means on each bar cooperating with the movement of the head and the respective dog for that bar to make and break the operative connection between the bar and the dog in such a timed relationship to the movements of said head that the bars will be operated intermittently and in a predetermined order.

7. In a flat knitting machine, the combination with a series of thread carrier bars mounted side by side for reciprocating movement in parallel paths and thread guides on said bars for feeding threads to the needles of the machine, of a reciprocating head mounted for movement in a path parallel with and closely adjacent to said bars, means carried by said head for reciprocating said bars, and parts cooperating with said means and with the reciprocation of the head relatively to said bars to shift the driving connection from one bar to another in such a timed relation as to operate the bars alternately.

8. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, means carried by said head for reciprocating said bars comprising a plurality of dogs carried by said head, one for each bar, each of said bars having parts cooperating with its respective dog to releasably establish driving connections therewith serving to slide the bar longitudinally, and a cam on each bar operable through the relative motion of the bar and said head to shift

its respective dog after each stroke of the bar to render the dog ineffective during the next reciprocation of the head but to cause the dog then to reengage the bar and to drive it in the direction opposite to its preceding direction of movement.

9. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, means carried by said head for reciprocating said bars comprising a plurality of dogs carried by said head, one for each bar, each of said bars having parts cooperating with its respective dog to releasably establish driving connections therewith serving to slide the bar longitudinally, and a cam on each bar operable through the relative motion of the bar and said head to shift said driving connection following its respective thread feeding movement in one direction so as to drive it in the opposite direction after one complete reciprocation of the head, said cams, dogs and cooperating parts being so constructed and arranged that the bars will be operated in rotation.

10. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, dogs mounted on said head, one for each bar, each dog being provided with oppositely acting pawls, each of said bars having two shoulders to engage said pawls and thus to cause the head to drive the bar in opposite directions, a cam on each bar between said shoulders for causing the movement of said head relatively to the bar to bring said pawls into operation alternately, said parts associated with each bar being so related as to render the pawls inoperative to drive the bar during one reciprocation of the head immediately following an operative movement of the bar, and means for holding said bars against movement except when driven by said pawls.

11. In a flat knitting machine, a thread carrier bar mounted for longitudinal reciprocating movement and a bridge piece mounted rigidly on said bar and provided with two shoulders spaced apart for the engagement therewith of pawls for driving the bar in opposite directions and a cam on said bridge piece between said shoulders.

12. In a flat knitting machine, a bar structure according to preceding claim 11, in combination with a thread guiding finger on said bar, and said bridge piece being provided with a thread guiding aperture extending into the end thereof and leading the thread to a point directly above said finger and into position to be fed into the thread guiding means on the finger.

13. In a flat knitting machine, the combination with a plurality of thread carrier bars mounted

side by side for reciprocating movement in parallel paths and thread guides on said bars for feeding threads to the needles of the machine, of a reciprocating head mounted for movement in a path parallel with and closely adjacent to said bars, and means carried by said head for reciprocating said bars selectively, comprising a rod mounted on said head and relatively stationary with reference thereto, a plurality of dogs supported on said rod to rock around the axis thereof, each of said dogs including two pawls, and spring actuated means individual to the respective dogs and cooperating with said rod to hold the dogs releasably in either of two angular positions in which the pawls are in their respective operative positions.

14. In a flat knitting machine according to preceding claim 13, the provision of stop screws threaded into the opposite sides of each dog to engage said rod and thereby to determine adjustably the opposite limits of the oscillating movement of the dog.

15. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, dogs mounted on said head, one for each bar, each dog being provided with oppositely acting pawls, each of said bars having two shoulders to engage said pawls and thus to cause the head to drive the bar in opposite directions, a cam on each bar between said shoulders for causing the movement of said head relatively to the bar to bring said pawls into operation alternately, said parts associated with each bar being so related as to render the pawls inoperative to drive the bar during one reciprocating of the head immediately following an operative movement of the bar.

16. In a flat knitting machine, the combination with a plurality of thread carrier bars mounted side by side for reciprocating movement in parallel paths and thread guides on said bars for feeding threads to the needles of the machine, of a reciprocating head mounted for movement in a path parallel with and closely adjacent to said bars, dogs mounted on said head, one for each bar, each dog being provided with oppositely acting pawls, each of said bars having two shoulders to engage said pawls and thus to cause the head to drive the bar in opposite directions, a cam on each bar between said shoulders for causing the movement of said head relatively to the bar to bring said pawls into operation alternately, said parts associated with each bar being so related as to render the pawls inoperative to drive the bar during one reciprocation of the head immediately following an operative movement of the bar, and said parts associated with the several bars being so related and adjusted that the bars are driven in succession.

PAUL G. STROUD.
